(57) **CLAIM**

The ornamental design for a bottle holder, as shown and described.

DESCRIPTION

FIG. 1 is a top plan view of my new bottle holder;
FIG. 2 is a left side elevation, the right side being identical thereto;

FIG. 3 is a bottom plan view;

FIG. 4 is an enlarged front end elevation;

FIG. 5 is an enlarged rear end elevation;

FIG. 6 is a perspective view viewed during use with a baby bottle; and,

FIG. 7 is a perspective view of my new bottle holder as viewed during use with a baby bottle.

“The broken line showing of environment in the drawings is included for the purpose of illustration only and forms no part of the claimed design.”
